UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

RECEPTACLE FOR DRINKING-CUPS.

1,186,706.

Specification of Letters Patent. Patented June 13, 1916.

Application filed February 1, 1913. Serial No. 745,553.

To all whom it may concern:

Be it known that I, WILLARD E. SWIFT, a citizen of the United States, residing at Worcester, in the county of Worcester and 5 Commonwealth of Massachusetts, have invented a new and useful Improvement in Receptacles for Drinking-Cups, of which the following is a specification, accompanied by drawings forming a part of the same.

10 My present invention relates to a receptacle adapted to hold a package of drinking cups in convenient form for transportation and capable of being inserted bodily in a vending or dispensing cabinet without 15 breaking bulk. By means of my present improvement I am enabled to arrange the drinking cups in proper order for delivery individually from one end of the receptacle. These objects, among others, I accomplish 20 by means of a cardboard receptacle having its ends adapted for the delivery of a single drinking cup by an endwise movement and provided with means for retaining the package of drinking cups in the receptacle 25 as hereinafter described, the novel features being pointed out in the annexed claims.

Referring to the accompanying drawings, Figure 1 represents in perspective view my improved drinking cup receptacle filled 30 with drinking cups and ready for insertion in a dispensing or vending cabinet. Fig. 2 is a perspective view of the same, but with the lower end uppermost, and Fig. 3 is a sectional view of the lower end of a 35 dispensing cabinet, showing the drinking cup receptacle inserted therein.

Similar reference characters refer to similar parts in the different figures.

My improved receptacle consists of a 40 cardboard box 1 rectangular in cross section and of suitable size in cross section to receive a package of drinking cups 2. The box 1 is open at each end and the drinking cups are packed therein in uniform positions, with the same sides of the cups up- 45 permost and with the tops and bottoms of the cups in the same direction. As represented in Figs. 1 and 2, the cups are placed in the box with their open sides lowermost, 50 with the bottom 3 of each cup next the side 4 of the box and with the top 5 of each cup next the side 6, and with the longitudinal sides of each cup lying next the sides 7 and 8 of the box.

55 The sides 4 and 6 of the box are sheathed

so that, when the box is supported on either end by the longer sides 7 and 8, a space 9, Fig. 1, will be left between the ends of the shorter sides 4 and 6 and the support of the receptacle of sufficient width to permit the withdrawal endwise of the lowermost drinking cup. At the center of each end of the longer sides 7 and 8 I provide notches 10, 11 and 12, 13. These notches are deeper than the ends of the shorter sides 4 and 6 60 and are designed to receive a band 14 which, when drawn tautly lengthwise the box and through the notches, will hold the end drinking cups a short distance inside the ends of the shorter sides 4 and 6. The band 65 14 is weakened at its center by a row of perforations 15. When the band 14 is applied to the box, the perforations 15 are brought over the center of the lowermost drinking cup, as shown in Fig. 2, and the 70 opposite ends of the band are lapped or glued together, as shown at 16, Fig. 1. The open ends of the box may then be closed by covers or wrapping paper, or other convenient means, forming an inclosed package 75 80 suitable for transportation, with the drinking cups arranged therein in proper position to be individually delivered from a dispensing cabinet such as that, for example, which is partially shown in sectional view 85 in Fig. 3 of the drawings.

For use in the dispensing cabinet, the covers or other wrappings of the receptacle are removed and the receptacle is inserted in the cabinet in the position shown in sectional view at 17, Fig. 3, with the ends of the longer sides 7 and 8 resting upon a shelf 18 of the cabinet. The band 14 is then seized at the upper end of the receptacle and pulled apart at its weakened portion, on the perforations 15. The severed band is then withdrawn, allowing the drinking cups to rest upon the shelf 18 with the lowermost cup in position to be engaged by a withdrawing hook 19 attached to a slide 20 having a curved handle 21 by which it is operated by the attendant. By the reciprocating motion of the slide 20 and withdrawing hook 19, the cups are individually withdrawn through the space 9 of the receptacle 90 and a corresponding space 22 in the front wall of the dispensing cabinet 23. By shortening the sides 4 and 6 at opposite ends of the box, I avoid the danger of placing the drinking cups in the receptacle in a wrong 100 105 110

position, as the receptacle is equally operative whichever end may be placed uppermost.

I claim,

- 5 1. A package of collapsed drinking cups for insertion in a dispensing cabinet, comprising an open-ended box adapted to fit loosely in said cabinet and containing a stack of such cups, and a band wound 10 lengthwise around said box and stack across the ends thereof, said band being weakened adjacent that end of the box, and stack which corresponds to the delivery opening of the cabinet, whereby said band may be 15 broken and removed by tension applied at the opposite end of the package, after the latter is inserted in the cabinet.
2. A receptacle for drinking cups, comprising a box having an opening in one end, 20 with one of its sides shorter than the adjacent sides to provide a space for the delivery of drinking cups therethrough, the longer sides having notches in their ends, and a cup retaining band wound lengthwise around the 25 box and held in said notches, said band having a weakened section where it crosses said opening whereby said band may be broken and removed by tension applied thereto at the opposite end of the box.
- 30 3. A receptacle for drinking cups, comprising a box having an opening in one end, and a band wound lengthwise around said box and across said opening with its ends

overlapped and united at the opposite end of the box, said band having a weakened 35 section where it crosses said opening, whereby the band may be broken at said opening and removed from the receptacle by tension applied to the band at the end of the box opposite the opening.

40 4. A receptacle for drinking cups, comprising a box with an opening in one end, and a cup retaining band extending across said opening and into exposed position at the other end of the box, said band having a 45 weakened section adjacent said opening, whereby the band may be broken and withdrawn by tension applied to it at the end of the box opposite said opening.

45 5. A receptacle for drinking cups, comprising a box having an opening in one end, two opposing sides of said box having notches at the end of the box provided with said opening, and a breakable cup retaining band extending across said opening, through 50 said notches and into exposed position at the other end of the box, said band being weakened adjacent said opening, whereby said band may be withdrawn by tension applied to its exposed portion.

Dated this 29th day of January, 1913.
